Primary Examiner — Ian Simmons*Assistant Examiner* — Dana L Meyrow(74) *Attorney, Agent, or Firm* — Brinks Gilson & Lione(57) **CLAIM**

We claim the ornamental design for a hand hygiene bottle, as shown and described.

DESCRIPTION

FIG. 1 is a perspective view of a hand hygiene bottle of the present invention;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof; and,

FIG. 8 is another perspective view thereof.

The evenly-dashed broken lines in the drawings illustrate the portions of the design that form no part of the claim. The dotted broken lines in the drawings define the bounds of the claim and form no part thereof.
